DRAINAGE VALVE SYSTEM

George T. Brown, Somerville, Mass.

Application March 6, 1947, Serial No. 732,902

3 Claims. (Cl. 303—38)

1

This invention relates to fluid pressure systems, and more particularly to a drainage valve and valve-operating means adapted to be applied to such systems for draining liquid and other foreign matter therefrom.

In fluid pressure systems, such as those used in the air brake and general control systems of motor busses and the like, liquids, comprising mostly water, collect within the system due to condensation of the moisture contained within the air. When this water, along with accumulated oil and sludge, is not frequently drained, it will interfere with the operation of the system, for the reason that it will rot the rubber diaphragms and gaskets and will also foul the various operating elements, thereby to cause sluggish operation of the entire air pressure system. Furthermore, an overaccumulation of water within the system may freeze, and thereby impair the operativeness of the system.

It has been the practice heretofore, in discharging such foreign matter from an air pressure system, to place manually operated valves at the bottom of the air reservoir. Thus, it is apparent that when such systems are used on motor busses, the reservoirs are frequently located in rather inaccessible positions and, therefore, operators will frequently neglect to open the manually operable drain valves at the necessary intervals.

It is, therefore, a primary object of the present invention to provide an air-pressure system with an improved drainage valve mechanism which may be actuated, while the system is in operation, without dropping the air pressure below a predetermined value.

A further object of the present invention is to provide, with an air-pressure system, a drainage valve mechanism which may be remotely controlled by and at the will of an operator.

A still further object of the present invention is to provide such a drainage valve mechanism which may be readily applied to any standard type of air-pressure system without necessitating any changes in the system proper.

With the above and other objects in view, as will hereinafter appear, the invention comprises the devices, combinations, and arrangements of parts, hereinafter set forth and illustrated in the accompanying drawings, of a preferred embodiment of the invention, and the advantages obtained thereby will be readily understood by those skilled in the art.

In the drawings,

Fig. 1 represents a side elevation, partly in section, of the present drainage valve,

2

Fig. 2 represents a sectional view taken substantially along the line 2—2 of Fig. 1.

Fig. 3 is a diagrammatic illustration of an air-pressure system to which the present drainage valve is attached.

Fig. 4 is a diagrammatic view illustrating the electrical system which is used in conjunction with the present drainage valve.

Fig. 5 represents, on an enlarged scale, a portion of the valve mechanism disclosed in Fig. 1.

Referring particularly to Figs. 1, 2, and 3, the present drainage valve comprises a substantially hollow casing 10 having provided therein, a pair of threaded apertures 11 and 12 in which are secured, respectively, an inlet tube 13 and an outlet tube 14. The inlet tube 13 is adapted to be secured to the lower portion 15 of a usual type of air reservoir 16. Fig. 3 discloses a simplified version of a usual type of air-pressure system comprising an air compressor unit 17 which is connected to the air reservoir 16 by means of a delivery conduit 18. Thus, the air compressor 17 is adapted to supply air under pressure to the reservoir 16, which functions to store such air for use by a plurality of air-actuated means which receive the air from the reservoir 16 by means of a conduit 19.

Referring particularly to Figs. 1, 2, and 5, the present casing 10 is formed with a substantially horizontally disposed bore 20, which communicates with a substantially vertically disposed bore 21 extending through the casing to open up at the lower portion thereof. A flange 22 is formed about the lower portion of the casing 10 and secured to this flange is a hollow cup member 23. The cup member 23 is also provided with a flange 24, which is secured to the flange 22 by means of suitable bolts 25 and nuts 26. As best seen in Fig. 1, the cup 23 is provided with a bore 27 which is disposed in vertical alignment with the bore 21 of the casing 10. The forward portion of the casing bore 20 is threaded, as at 28, thereby to receive a threaded bulkhead 29, which is provided with a central bore 30 communicating directly with the casing bore 20. Also received within the threaded portion 28 of the bore 20 is a threaded stud 31 having a hexagonal head portion 32 which abuts against a face portion 33 of the casing 10, whenever the same is seated within the bore 20. Still referring to Fig. 1, the bulkhead 29 is provided with a shoulder portion 34, which is adapted to engage an annular shoulder 34' formed within the bore 20 and thus, the bulkhead 29 is held within a predetermined position within the bore 20, whenever the same is seated

home. From this, it will be understood that the bulkhead 29 and the threaded stud 31 will always be spaced a predetermined distance apart, longitudinally of the bore 20, thereby to form a substantially cylindrical chamber 35 which communicates with the threaded aperture 11 by means of a short conduit 36.

The rear portion of the casing conduit 20 has communicating therewith, an aperture 37 which has threaded therein, a cylindrical sleeve member 38 which is provided with a longitudinally disposed bore 39. Slidably received within the bore 39 is a valve-actuating pin 40, the inner portion of which is provided with an aperture 41 in which is received a rear end portion of a valve stem 42. The other end of the valve stem 42 has formed thereon, a valve head 43, which is provided with a conical shoulder portion 44, an annular flange 45, and a shoulder member 46. Referring particularly to Figs. 1 and 5, it is to be understood that the valve stem 42 extends loosely through the bulkhead bore 30, so that the valve head 43 is disposed within the cylindrical chamber 35. Cooperating with the conical shoulder 44 of the valve head 43 is a conical valve seat 47 formed at the right-hand end portion of the bulkhead bore 30. An annular recess 48, concentrically positioned about the bore 30 and within the face portion of the bulkhead 29, provides clearance for the valve head 43. The stud 31 is provided with a circular recess 49 which is adapted to receive a portion of the valve head 43. This recess 49 functions primarily as a seat for a coil spring 50, one end of which abuts the base portion of the recess 49, and the other end of which engages the annular flange 45 of the valve head 43, to the end that the shoulder portion 44 of the valve head is biased into engagement with the valve seat 47. The shoulder portion 46 of the valve head 43 is surrounded by the spring 50 and acts to confine the spring in its proper relation with the valve head 43. From the above, it is to be understood that the spring 50 normally functions to close the above described valve, so that no communication may be normally had between the inlet tube 13 and the bore 21 of the casing 10. However, it is to be further understood that, if the valve pin 40 is shifted toward the right-hand side of the casing, it will be effective to unseat the valve mechanism to the end that the inlet tube or conduit 13 would be placed in direct communication with the bore 21 of the casing 10.

Referring particularly to Fig. 1, the sleeve 38 has provided at one end thereof, a head member 51, and between this head member and a block 52 provided on the casing 10, is positioned a cylindrically wound electrical coil 53. Projecting upwardly from the block or seat 52 is a non-magnetic yoke 54, which has its mid-portion disposed substantially in parallelism with the pin 40 and its free end portion is bent downwardly, as at 55. This yoke 53 carries a cross pin 56, upon which is pivotally mounted a magnetic flapper 57, which is adapted to be shifted toward the coil 53, whenever the same is energized. From this, it is to be understood that, upon energization of the coil 53, the flapper 57 will move in a right-handed direction, thereby to engage the distal end portion of the pin 40, to the end that the hereinabove described inlet valve mechanism will be unseated; it being understood that the strength of the coil 53 is sufficient to overcome the biasing force of the spring 50. The flapper element 57 has formed thereon, a projection 58 which is adapted to cooperate with the depending portion 59 of

the yoke, thereby to prevent the flapper member from moving to the left beyond a predetermined angle.

The lower portion of the casing bore 21 is provided with a pair of concentric bores 59 and 60, and force-fitted within the bore 59 is a cylindrical bulkhead member 61 which is provided with an aperture 62, the lower shoulder portion of which functions as a valve seat for cooperation with a valve ball 63. This valve ball 63 has depending therefrom, a stem 64 which is received within a pair of base members 65 and 66, each of which is disposed upon an opposite face of a flexible diaphragm member 67. This stem 64 is threaded and receives a pair of oppositely disposed nuts 68 and 69, which function to bias the base members 65 and 66 toward each other to the end that the entire valve ball assembly is carried upon the diaphragm 67, which is sandwiched between the flanges 22 and 25. Thus, the diaphragm 67 functions as a gasket to prevent the egress of fluid from between the flanges 22 and 24, and it also functions as a flexible holder for the valve ball assembly. Disposed within the bore 27 of the cup member 23 is a coil spring 70, the upper end portion of which is adapted to surround the nut 69 and engage the base member 66. The lower end portion of the spring 70 engages a cupped thrust member 71, which is mounted upon the upper end of an adjusting screw 72 threaded in the lower portion of the cup member 23. From this, it is to be understood that the spring 70 functions normally to bias the valve ball 63 into engagement with the bulkhead 61, thereby to prevent communication between the bore 21 and the bore 60. It is to be particularly noted that the outlet tube 14 is threaded within the aperture or port 12, which communicates directly with the bore 60. Thus, as long as the valve ball is in its normally closed position, the outlet tube 14 cannot communicate with the bore 21 or with the reservoir 16. By the same token, whenever this lower exhaust valve is opened, the outlet 14 will be placed in direct communication with the bore 21.

As hereinabove noted, the present drainage valve is adapted to have its inlet tube 13 connected to the bottom portion of an air reservoir 16; and, from this, it will be apparent that any foreign matter, such as water, oil, or an emulsion of oil and water which collects within the reservoir 16, will tend to flow into the inlet tube 13 and, consequently, into the cylindrical chamber 35 of the casing 10. However, as long as the check-valve unit, comprising the valve head 43 and the bulkhead 34, remains closed, this accumulated foreign matter from the reservoir 16 cannot find its way into the bores 20 and 21 of the casing 10. Upon energization of the coil 53, as hereinabove described, the check valve will be opened to the end that the foreign matter will find its way from the inlet 13 to the interior portions of the casing 10. The present invention contemplates that the spring 70 will be so adjusted that the fluid pressure within the air reservoir 16 will be effective, upon the opening of the check valve, to force the valve ball 63 away from the bulkhead 61, only in the event that the pressure of the fluid reaches a predetermined value. In this connection, it might be well to point out that most all states have laws regulating the installation and use of air pressure systems upon vehicles engaged as common carriers. For example, some states require that the motor bus air pressure brake systems have an air pressure of 60 pounds per square inch at all times during the operation

of such vehicles. From this, it is to be understood that, in order legally to operate the present valve system, it will be necessary to adjust the spring 70, so that the valve ball 63 cannot open until the air pressure within the reservoir 16 rises above 60 pounds per square inch. Thus, the present invention is adapted to be used during the operation of the air pressure system, for the reason that the use thereof will not reduce the required air pressure within the air pressure system below the required legal limit. Therefore, it is apparent that the present drainage valve mechanism may be operated while the vehicle, upon which it is used, is in operation and, therefore, the operator of the vehicle may purge his air pressure system of foreign matter at frequent intervals, thus obviating the necessity of deferring this purging action until the vehicle is put out of operation.

The hereinabove noted adjusting screw 72 functions as an adjusting means to the end that the spring 70 may be calibrated for any predetermined air pressure. In other words, by adjusting the screw 72, it will be apparent that the exhaust valve may be made responsive to various predetermined fluid pressures. The distal end portion of the adjusting screw 72 is provided with a pair of nuts 73, 73, which function to lock the screw 72 in any one of its adjusted positions.

Referring particularly to Figs. 2 and 4, the present coil 53 is provided with a pair of oppositely disposed terminals 74 and 75, of which the former may be connected to a grounded element by means of an electrical conductor 76. The terminal 75 may then be connected with an electrical conductor 77 to one terminal of a knife switch 78 which may be mounted within comfortable reach and visibility of the vehicle operator. Whenever the knife switch 78 is thrown into operative position with its cooperating terminal 79, the coil 53 is adapted to be energized, for the reason that the terminal 79 is connected to one side of an electrical power source, such as a battery 80. The other side of the battery 80 may be connected by means of a conduit 81 to a grounded element of the vehicle, thus, to complete the coil circuit. If desired, the knife switch 78 may be connected, by means of a conductor 82, to one side of an electrical buzzer 83, the other side of which may be appropriately grounded by means of a conductor 84. Therefore, whenever the knife switch 78 is closed for the purpose of energizing the coil 53, it will also be effective to energize the buzzer 83, to the end that the human operator will be advised as to whether the electrical system is working properly. Of course, a visual signal may be substituted for the audible buzzer 83. Furthermore, with such an audible or visual signal placed within the system, the operator will not be likely to leave the knife switch closed beyond the necessary time interval required for purging the system.

With the present valve mechanism, as hereinabove described, there is some possibility that, upon the opening of both the check and exhaust valves, air and moisture will be blown out through the sleeve bore 39 about the pin 40. This condition may be readily obviated by providing a packing about the pin 40, but the present invention contemplates the provision of a third bulkhead 85 which is adapted to be threaded into the bore 26 so as to be seated against a shoulder 86. As may be best seen in Fig. 5, this bulkhead 85 is provided with a shouldered aperture 87 through which passes the valve stem 42. It is to be understood that whenever the check valve is closed the

end portion of the pin is spaced from the bulkhead 85, but whenever the coil 53 is energized it will be effective to shift a conical shoulder portion 88 of the pin 40 into engagement with the bulkhead shoulder 87 thereby to prevent the fluids from blowing out through the sleeve bore 39 as the check valve is opened. This sealing means or valve will, of course, in no way interfere with the operation of the check and exhaust valves.

From the above, it is to be understood that the present drainage valve system comprises a substantially self-contained unit which may be readily connected to any usual type of air pressure system by merely connecting the inlet tube 13 to the reservoir of such a system. Use of the present invention requires no elaborate modification to be made in the air pressure system to which it is to be attached. Thus, existing air pressure systems may have the present drainage valve mechanism applied thereto with a minimum expenditure of time and money.

I claim:

1. Drainage mechanism for a fluid pressure system, comprising, an inlet conduit adapted to be attached to the system so as to be in communication with the interior thereof, an outlet conduit connected with said inlet conduit, a mechanically operable valve and a fluid pressure operable valve connected in series between said inlet and outlet conduits so that said conduits will communicate with each other only upon the opening of both of said valves, said mechanically operable valve being disposed between the other valve and said inlet conduit, spring means for biasing said fluid pressure operable valve to a normally closed position and being calibrated so that its valve will open in response to the force of the fluid pressure within said system when the pressure of said fluid rises above a predetermined value only, means for adjusting said spring so that its valve will be rendered responsive to various predetermined fluid pressure values, electro-magnetic means for shifting said mechanically operable valve to an open position, a manually controlled switch for energizing said electro-magnetic means at the will of an operator, and signal means connected in circuit with said switch so as to be energized in synchronism with said electro-magnetic means.
2. Drain valve mechanism for a fluid pressure system, comprising, a casing having an inlet at one end thereof adapted to be attached to the bottom portion of the reservoir so as to be in communication with the interior of the reservoir, a conduit disposed longitudinally of said casing so as to communicate with said inlet and to open out at the other end of said casing, a hollow cup disposed against the other end of said casing and over said conduit, a liquid-tight diaphragm disposed between said casing and said cup, an outlet disposed within the casing wall and in communication with said casing conduit at a location adjacent said diaphragm, a normally closed first valve disposed within said casing conduit between said inlet and said outlet, means for opening said first valve thereby to place said casing conduit in communication with the interior of said system, a second valve disposed in engagement with said diaphragm and within said casing conduit between said outlet and said first valve, and spring means disposed in engagement with said diaphragm and within said cup for biasing said second valve to a normally closed position, said second valve being adapted, upon the opening of

said first valve, to open in response to the system fluid pressure whenever the same exceeds a pre-determined value only.

3. Drain valve mechanism for a fluid pressure system, comprising, a casing having an inlet at one end thereof adapted to be attached to the bottom portion of the reservoir so as to be in communication with the interior of the reservoir, a conduit disposed longitudinally of said casing so as to communicate with said inlet and to open out at the other end of said casing, a hollow cup disposed against the other end of said casing with the hollow portion of said cup disposed coaxially of said casing conduit, a liquid-tight diaphragm disposed between said casing and said cup, an outlet disposed within the casing wall so as to be in communication with and at right angles to said casing conduit at a location adjacent one side of said diaphragm, a normally closed first valve disposed within said casing conduit between said inlet and said outlet, means for opening said first valve thereby to place said casing conduit in communication with the interior of

5

10

said system, a second valve carried upon one side of said diaphragm and within said casing conduit between said outlet and said first valve, and spring means disposed in engagement with said diaphragm and within said cup for biasing said second valve to a normally closed position, said second valve being adapted, upon the opening of said first valve, to open in response to the system fluid pressure whenever the same exceeds a pre-determined value only.
